US00D516398S

(12) **United States Design Patent** (10) Patent No.: **US D516,398 S**
Janson (45) Date of Patent: **** Mar. 7, 2006**

(54) **POWER TOOL HOUSING**

(75) Inventor: **John C. Janson**, East Dundee, IL (US)

(73) Assignee: **WMH Tool Group, Inc.**, Elgin, IL (US)

(**) Term: **14 Years**

(21) Appl. No.: **29/193,042**

(22) Filed: **Nov. 3, 2003**

(51) LOC (8) Cl. **08-01**

(52) U.S. Cl. **D8/62**

(58) Field of Classification Search D8/61, D8/62, 67, 70; 173/170, 171, 217; 310/50; 451/344, 351, 353, 354, 355, 356, 357, 358, 451/359, 451, 456; 81/54, 474

(57) **CLAIM**

I claim the ornamental design for a power tool housing, as shown and described.

DESCRIPTION

FIG. 1 is a perspective view of a power tool housing according to my new design, the broken lines of the power tool housing are for illustrative purposes only and form no part of the claimed design;

FIG. 2 is a front elevational view of the power tool housing of FIG. 1, the broken lines of the power tool housing are for illustrative purposes only and form no part of the claimed design;

FIG. 3 is a rear elevational view of the power tool housing of FIG. 1, the broken lines of the power tool housing are for illustrative purposes only and form no part of the claimed design;

FIG. 4 is a plan view of the power tool housing of FIG. 1, the broken lines of the power tool housing are for illustrative purposes only and form no part of the claimed design;

FIG. 5 is a left-side elevational view of the power tool housing of FIG. 1 with the rear handle shown in a first position, the broken lines of the power tool housing are for illustrative purposes only and form no part of the claimed design; and,

FIG. 6 is a right-side elevational view of the power tool housing of FIG. 1 with the rear handle shown in a second position, the broken lines of the power tool housing are for illustrative purposes only and form no part of the claimed design.
